Primary Examiner — Mark A Goodwin(74) *Attorney, Agent, or Firm* — Haynes and Boone, LLP(57) **CLAIM**

The ornamental design for the tie, as shown and described.

DESCRIPTION

FIG. 1 shows a front perspective view of a tie;
FIG. 2 shows a top view of the tie of FIG. 1;
FIG. 3 shows a bottom view of the tie of FIG. 1;
FIG. 4 shows a right side view of the tie of FIG. 1;
FIG. 5 shows a left side view of the tie of FIG. 1;
FIG. 6 shows a right side view of the tie of FIG. 1; and,
FIG. 7 shows the left side view of the tie of FIG. 1.
The broken line showing of the ends of the claim included
for the purpose of illustrating portions of the tie and forms
no part of the claimed design.

1 Claim, 3 Drawing Sheets# US D863,946 S
